CLAIM

The ornamental design for a capsule for solid detergent, as shown and described.

DESCRIPTION

FIG. 1 is a perspective view of the first embodiment of the capsule;

FIG. 2 is a top plan view of the first embodiment of the capsule;

FIG. 3 is a bottom plan view of the first embodiment of the capsule;

FIG. 4 is a perspective view of the second embodiment of the capsule;

FIG. 5 is a top plan view of the second embodiment of the capsule; and,

FIG. 6 is a bottom plan view of the second embodiment of the capsule.

The portion of the sidewalls not visible in FIGS. 1 and 4 continues uniformly around the capsule on either side of the notch.
